UNITED STATES PATENT OFFICE.

LAZARD KAHN, OF HAMILTON, OHIO, ASSIGNOR TO F. & L. KAHN & BROS.,
OF SAME PLACE.

DESIGN FOR A GAS-STOVE.

SPECIFICATION forming part of Design No. 23,505, dated July 24, 1894.

Application filed June 2, 1894. Serial No. 513,324. Term of patent 7 years.

To all whom it may concern:

Be it known that I, LAZARD KAHN, a citizen of the United States, residing at Hamilton, Butler county, Ohio, have invented and produced a new and original Design for Gas-Stoves, (Case B,) of which the following is a specification, reference being had to the accompanying drawing, showing the same in perspective.

My design is characterized by a table-like stove-body A mounted on legs and having burner openings B in the top thereof, a box-like broiler C depending from the body be-

tween the legs thereof, and a box-like oven D disposed upon the top of the body over the 15 broiler C and forming, in visual effect, a continuation of the broiler upwardly beyond the horizontal plane of the top of the stove-body.

What I claim is—

The design for a gas stove substantially as 20 shown and described.

LAZARD KAHN.
